Carpets

3235

UNITED STATES PATENT OFFICE.

HERBERT ROBINSON, OF HALIFAX, ENGLAND, ASSIGNOR TO JOSEPH WILD & CO., OF NEW YORK CITY.

DESIGN FOR A CARPET-PATTERN.

Specification forming part of Design No. 5,652, dated March 12, 1872.

Specification describing a new and original Design for Carpets, invented by HERBERT ROBINSON, of Halifax, in the county of York, England.

The accompanying photograph represents my new design.

This invention relates to a new design for a carpet, which is composed of three kinds of ornamental figures, A, B, and C, all of which are clearly represented.

The figure A is a large quatréfoil, embracing a curvilinear octagon, *a*, and surrounded by arches *b b* of flowers. The figure B has a more irregular outline, and is embraced by

wreaths of flowers; while C is a square with depressed corners and straight-lined ornamentation, as shown.

I claim as my invention—

1. The design of the figure A, as shown.
2. The design of the figure B, as shown.
3. The design of the figure C, as shown.
4. The design for a carpet, containing the figures A, B, and C, as shown.

HERBERT ROBINSON.
